WILLIAM E. BERTRAM, OF BROOKLYN, NEW YORK, ASSIGNOR TO INTERNATIONAL
TYPESETTING MACHINE COMPANY, OF NEW YORK, N. Y., A CORPORATION OF NEW
YORK.

LINOTYPE-MACHINE.

1,116,218.

Specification of Letters Patent.

Patented Nov. 3, 1914.

Application filed November 23, 1911. Serial No. 661,942.

To all whom it may concern:

Be it known that I, WILLIAM E. BERTRAM, a citizen of the United States, residing at Brooklyn, in the county of Kings and State of New York, have invented new and useful Improvements in Linotype-Machines, of which the following is a specification.

The present invention relates to improvements in linotype machines and more especially to those of the Mergenthaler type disclosed, for example, in United States Letters Patent, No. 436,532 granted September 16, 1890, and the primary object of this invention is to provide simple and improved means for preventing a restarting of the machine after the operation thereof has been interrupted owing to an improper positioning of the matrices relatively to the mold and while this improper relation of the parts exists, thereby preventing injury or damage to the matrices and avoiding splashing of the molten metal over the operative parts of the machine.

In machines of the linotype class as disclosed in the aforesaid patent, the driving clutch is controlled by the elevator which conveys each line of matrices and spacers to the mold preparatory to the casting operation, and means is provided whereby the clutch is automatically disengaged to interrupt the operation of the machine should the elevator fail to properly present the line of matrices or spacers to the mold, owing, for example, to an excess number of matrices in the line. Practical use, however, has shown that, in operating machines of the construction shown in said patent, it was possible for the operator to manipulate the hand lever to restart the machine after this operation had been interrupted, thereby permitting the machine to complete the cycle of operations before resetting of the parts, with the consequent danger of damaging the matrices and permitting molten metal to escape, owing to the incorrect positioning of the matrices with respect to the mold, and the escape of such metal on the operative parts of the machine has in practice caused considerable delay and trouble. Furthermore, said elevator and the clutch-controlling parts are mounted on a frame which is adapted to be swung open to permit re-arrangement of the line of matrices by hand, and this opening movement of the frame has heretofore carried the clutch-controlling

means mounted thereon out of engagement with that portion of the clutch-controlling means which is mounted on the main frame, and has allowed the spring which tends to throw the clutch into engagement to act and thus start the machine into operation and hence allow the molten metal to be pumped through the mold while the line of matrices was not presented in a manner to close the mold. These objections have been obviated by the present invention, the preferred embodiment of which is shown in the accompanying drawings, wherein—

Figure 1 is a plan view partly in section of the driving clutch and its controlling means provided with a locking device constructed in accordance with the present invention; Fig. 2 is a detail view of the locking device showing the same in position to prevent setting of the clutch to cause operation of the machine; Fig. 3 is a side elevation partly in section of the mechanism as shown in Fig. 1; and Fig. 4 is a perspective view of the automatic lock and the parts cooperative therewith.

Similar parts are designated by the same reference characters in the several views.

The main driving pulley 1 is mounted revolubly on a driving shaft 2, this pulley having an internal clutch face to coöperate with the friction clutch shoes 3, these shoes being movably connected to a clutch member 4, the latter being keyed or otherwise fixed to the shaft 2. The clutch shoes are connected to operating links 5 and these links are operatively connected to an actuating head 6, the latter being fixed to the outer end of a spindle 7 which is slidable axially through a head 8 in the outer end of the shaft 2 and operates longitudinally in a central bore in the shaft 2, the inner end of this spindle being pinned to a sliding clutch actuating collar 9 which is mounted loosely on the shaft 2. A compression spring 10 operates between the stationary head 8 and the head 11 fixed to the spindle and this spring tends to set the clutch in driving condition and to maintain it in such condition. The clutch is controlled by a bell-crank lever 12, the latter being pivoted at 13 on a part of the stationary frame 14, and one arm 15 of this bell-crank lever bears against the clutch operating collar 9, the other arm 16 of the bell crank lever having a pin 17 which engages in the forked

end of a bar 18, the latter having a slotted end which is guided by the pin 19. The mold wheel 20 carrying the mold 21 co-operates with a line of matrices to cast a slug therefrom. Each line of matrices 22 is presented to the mold by an elevator 23. This elevator carries a set-screw 24 which is arranged to co-operate with a pin 25 on the upper end of a controlling bar 26. This controlling bar is normally held yieldably in elevated position by a spring 27 and it carries a projection 28 which is arranged in co-operative relation with a sliding pin 29, the latter being pushed toward the projection 28 on the controlling bar by the mold projection 30 on the mold wheel. When the elevator operates properly to correctly present a line of matrices to the mold, the set-screw 24 on the elevator will operate through the pin 25 to depress the controlling bar 26 and thereby carry the projection 28 into a position to clear the pin 29 when the latter is moved forward and, hence, the controlling bar will remain inoperative. If, however, the elevator fails to operate to an extent sufficient to correctly present the line of matrices to the mold, the set-screw 24 will fail to depress the controlling bar 26 sufficiently to cause the projection 28 thereon to clear the pin 29, and when the latter is pushed forward by the mold wheel will operate upon the projection 28 to rock the controlling bar 26, and through the agency of mechanism to be described, the clutch will be automatically set in inoperative condition and the operation of the machine will be interrupted. According to the present invention, the controlling bar 26 is arranged to bear upon one end of a lever 31, this lever 31 being fulcrumed on a fixed pivot 32 and the opposite end of the lever 31 bears against a roller or projection 33 on one arm of a bell-crank lever 34, the latter being pivoted at 35 within a housing 36 and it has an arm 37 which will operate to lock the hand lever 39 from operation. The roller or projection 33 is held in engagement with the lever 31 by a tension spring 38. The hand lever 39 which enables the operator to start and stop the machine is pivoted on the pin 19 and the angularly extending arm 40 thereof is provided with a hook-shaped lug or projection 41. The arm 40 of the controlling handle or starting device is also operatively connected to the bar 18 by a link 42. When the operative parts of the machine are in proper relation, the handle 39 can be operated to set the clutch in driving condition to start the machine as the spring 38 will hold the locking arm 39 clear of the locking lug or projection 41 on the handle, the setting of the clutch in driving condition being effected by a downward movement of the bar 18, with reference to Fig. 1, a rocking of the bell-crank lever 12, and expansion of the

spring 10 which operates to force the clutch shoes 3 into engagement with the clutch face on the main driving pulley 1. However, should the elevator 23 fail to travel a sufficient distance to correctly present a line of matrices to the mold, the controlling bar 26 will not be depressed a distance sufficient to cause the projection 28 thereon to clear the pin 29, and this pin will be pushed forward by the mold wheel and will operate on the projection 28 to rock the controlling bar 26. This controlling bar will then bear against the adjacent end of the lever 31 and the opposite end of this lever will push against the roller or projection 33, thereby causing the arm 37 to bear against the lug or projection 41 on the arm 40 and to shift the handle 39 into a position to set the clutch in inoperative condition, thereby interrupting automatically the operation of the machine. This arm 37 after setting the clutch in inoperative condition engages beneath the lug or projection 41 and thereby locks the handle 39 from movement in a direction to restart the machine and the machine cannot be restarted by manipulation of the handle 39 until the elevator has been properly reset, whereupon the lever 31 will be released by the controlling bar 26, and the bell-crank lever 34 will return to normal inoperative position under the influence of its spring 38, the arm 37 releasing the lug or projection 41 and then permitting the handle 39 to be operated to set the machine in operation. The housing 36 which covers the locking member 34 and the co-operative parts prevents tampering with the locking mechanism and, hence, it is necessary for the operator to restore the machine to proper condition before attempting to restart it.

The elevator 23 is mounted to slide in a frame 43 commonly known as the vise frame which is pivoted at its lower end and is adapted to be swung outwardly to facilitate re-arrangement of the line of matrices by hand, as shown and described fully in the patent to Mergenthaler No. 436,531 granted September 16, 1890. Upon this vise frame are also mounted the pin 29, the controlling bar 26, and the lever 31. Opening movement of the vise frame 43 carries the lever 31 out of engagement with the roller 33 and permits the spring 38 to disengage the arm 37 from the locking projection 41 on the starting device. In machines as heretofore constructed, the opening movement of the vise frame would allow the clutch spring 10 to act without interference to restart the machine, but according to the present invention, the arm 40 and the link 42 form a toggle which, when the clutch is thrown out of operation, effectually locks the clutch against the action of the spring 10, and the machine cannot be restarted unless the handle or starting device 39 is positively pulled

forward. When the clutch is automatically disengaged to prevent operation of the machine, owing to incorrect positioning of the line of matrices before the mold by the elevator, the arm 37 of the bell-crank 34 operates to positively straighten the toggle and to lock it in such condition so that the machine cannot be restarted by jarring of the handle or starting device 39 when the vise frame is released and swung into open position.

I claim as my invention:—

1. In a linotype machine, the combination of a main driving clutch, a starting device for the machine controlling said clutch including a handle, mechanism operative automatically by the means for presenting the matrices to the mold to shift said starting device into position to interrupt operation of the machine, and means acting directly on said handle to lock said device in such position.

2. In a linotype machine, the combination of a clutch for driving the machine, a starting device coöperative with the clutch and provided with a locking projection, a locking member adapted to coöperate with said projection, and mechanism controlled by the means which presents the matrices to the mold for positively setting said locking member in engagement with said locking projection.

3. In a linotype machine, the combination of a main driving clutch, a starting device coöperative with the clutch and provided with a locking projection, mechanism controlled by the means which presents the matrices to the mold, and a locking member interposed between said starting device and said mechanism and operative by the latter to engage said projection and positively lock the starting device from operation.

4. In a linotype machine, the combination of a main driving clutch, a manual starting device connected to the clutch, controlling means provided with a locking projection, a locking member adapted to coöperate with said locking projection but normally disengaged therefrom, and mechanism controlled by the means which presents the matrices to the mold for moving the locking member into engagement with said projection to disengage the clutch and lock the starting device from operation.

5. In a linotype machine, the combination of a main driving clutch, a manually opera-

tive starting device for the clutch provided with a locking projection, a pivoted locking member having a part adapted to engage said projection, means for normally retaining said member in inoperative position, and mechanism operative automatically by the means which presents the matrices to the mold for moving said locking member into engagement with said projection to set the clutch in inoperative condition and lock the starting device from operation.

6. In a linotype machine, the combination of a main driving clutch, a movable handle having an angular arm operatively connected to the clutch and provided with a hook-shaped locking projection, a pivoted locking lever having one arm to coöperate with said locking projection on the handle, and mechanism controlled by the elevator which presents the matrices to the mold, said mechanism being operative upon said locking lever to force the handle into clutch-disengaging position and to lock said lever with said projection on the handle.

7. In a machine of the class described, the combination of a main driving clutch, a spring tending to engage said clutch, a vise frame capable of being moved into inoperative position, means mounted on said vise frame for presenting matrices to the mold and for automatically disengaging said clutch when the matrices are not properly presented to the mold, and a latch automatically set conjointly therewith for positively holding said clutch in disengaged condition when the vise frame is in inoperative position.

8. In a machine of the class described, the combination of a driving clutch, a spring tending to set said clutch in driving condition to operate the machine, a frame capable of assuming an inoperative position, means mounted on said frame and capable of automatically setting said clutch in inoperative condition, and an automatically operative latch interposed between said means and clutch to hold the clutch against the pressure of its spring when said frame is in inoperative position.

In testimony whereof I have hereunto set my hand in presence of two subscribing witnesses.
